UNITED STATES PATENT OFFICE.

EDWARD DUDLEY LEWIS, OF ELMIRA, NEW YORK, ASSIGNOR TO HEATER-MUFFLER CO., OF ELMIRA, NEW YORK, A CORPORATION OF NEW YORK.

MUFFLER.

1,024,688.

Specification of Letters Patent. Patented Apr. 30, 1912.

Application filed August 9, 1911. Serial No. 643,229.

To all whom it may concern:

Be it known that I, EDWARD DUDLEY LEWIS, a citizen of the United States, and resident of Elmira, in the county of Chemung and State of New York, have invented certain new and useful Improvements in Mufflers, of which the following is a specification.

This invention relates to mufflers for over-
coming the noise produced by engines that exhaust forcibly into atmosphere, and has for its object a device of the character mentioned that is simple and cheap in construction, and that is also highly efficient.

15 The muffler in question is specially designed for use in connection with gas engines of the explosion type from which the exhaust is expelled with such force that the noise is particularly objectionable.

20 Referring to the drawings:—Figure 1 is a central, longitudinal section of the muffler on the line 1, 1 of Fig. 2; and Fig. 2 is a cross-section on the line 2—2 of Fig. 1.

The muffler comprises a plurality of similar inter-communicating, hollow sections connected together, each section consisting, broadly speaking, of a chamber having inlet and outlet parts that are oppositely located in corresponding positions in each 25 section, and containing perforated partitions that cause the gas to take a circuitous course through the muffler and gradually transforms the pulsations of the noisy, explosive exhaust to a continuous noiseless discharge.

In the drawings the hollow sections are represented as concave, and made up from two similar concave members 1, 1, having flanged edges 2, 2, which are cheaply formed 30 by casting or stamping. These sections make a very cheap muffler for they are all made from the same pattern, and so are interchangeable, and besides the rounded, hollow chambers formed by them when assembled are specially well adapted to serve as expansion chambers, in which the gas may lose the pressure under which it is discharged from the engine. The perforated partitions 3 are, respectively, represented as

held between the flanges 2, 2 of the sections, 50 so that they are secured in place by the flanges when the latter are fastened together, by rivets or other means, in forming the sections. The perforated partitions 3 are also made to serve the purpose of deflectors to turn the gas as it enters the sections outwardly toward the perforations 4 (see Fig. 2) through which it passes in its course to the next section, and are adapted to that purpose by being formed with central, pyramidal projections 5, that extend in the opposite direction to that in which the gases flow. Thus, the gases are caused to flow through the muffler in a circuitous course, as indicated by the arrow, in which the gas is given an opportunity to expand as it enters the sections successively, and is also repeatedly choked back by the perforated partitions 3 till finally it exhausts from the muffler in a continuous discharge 70 that is noiseless. The end sections are provided with suitable coupling members 6.

The sections are connected to each other by metal rings 7 that have pliant flanges 8 adapted to be brought together so as to clamp and retain rigidly between them the edges of both the adjacent sections. Thus, it is obvious that the muffler can be built up from a supply of sections consisting of hollow members all of which are of one pattern, partitions all alike, and coupling rings all the same with the exception of those that serve for end couplings which have collars extending out from them as shown.

I claim:—

1. In a muffler, the combination of a plurality of intercommunicating hollow sections each formed of two identical oppositely-disposed centrally-perforated concave members having flanged edges, the members of the sections being all interchangeable and each section containing a perforated central partition-plate which is clamped in place by the flanges of its members; substantially as shown and described. 90

2. A muffler having, in combination, a plurality of oppositely-disposed concave members with adjoining edges, and rings

of U-shaped cross-section embracing and clamping said edges together.

3. A muffler having, in combination, two oppositely-disposed concave members with outwardly-projecting peripheral flanges, an intermediate baffle-plate with its periphery embraced between said flanges, and a clamp-

ing-ring of U-shaped cross-section embracing the flanges and securing said members and the baffle-plate together.

EDWARD DUDLEY LEWIS.
